JOEL TIFFANY, OF ALBANY, NEW YORK.

Letters Patent No. 73,133, dated January 7, 1868.

IMPROVED APPARATUS FOR PREPARING PAPER-STOCK.

The Schedule referred to in these Letters Patent and making part of the same.

TO ALL WHOM IT MAY CONCERN:

Be it known that I, JOEL TIFFANY, of the city and county of Albany, and State of New York, have invented a new and improved Process for Treating Paper-Stock for the Manufacture of Paper; and I do hereby declare that the following is a full and exact description thereof, reference being had to the accompanying drawings, and to the letters marked thereon.

The nature of my improvement consists in the manner of preparing my stock before putting the same into the reducing-vessel, the manner of preparing my reducing-liquor, the manner of bringing the stock and reducing-liquor together, and the means by which I apply my process.

First. The stock should be prepared by being cut, crushed, ground, or broken into small fragments, for the purpose of exposing a large surface to the action of the reducing-liquor, and for the greater facility of packing the same in the reducing-vessel. The stock thus prepared may be soaked or steamed so as to soften the parts of the stock, and also to admit of being more closely packed in the reducing-vessel. But if the stock has been thus soaked or steamed, before putting the same into the reducing-vessel, the water should, as far as possible, be removed from the pores and cells of the same by pressing, or the air should be exhausted from the reducing-vessel after the stock has been placed therein. The reason is obvious. The presence of water in the cells of the stock excludes the free access of the caustic or caustic liquors thereto, and ultimately reduces the strength of the caustic liquor by the per cent. of water present in the stock at the time of its introduction thereto. If the stock is to be soaked prior to the introduction of the reducing-liquor thereto, it should be soaked in a caustic liquor of the same character as that with which it is to be subsequently treated. But the presence even of the caustic liquor in the cells of the stock acts unfavorably upon the action of the reducing-liquor, when introduced according to my improved process, by reducing the temperature of the liquor, and consequently affecting its action upon the stock. For these reasons previous soaking and steaming of the stock before the introduction of the boiling liquor are not deemed to be an essential part of this process. The vacuum-process, consisting in exhausting the air from the reducing-vessel after the same has been charged with stock, and preparatory to the introduction of the reducing-liquor to the stock, may be resorted to with advantage when the conveniences exist for applying it. So likewise may the pneumatic-process, consisting in the forcing into the reducing-vessel atmospheric air to create a pressure upon the liquor and stock, to force the liquor into all the pores and cells of the stock, where conveniences to apply the same exist. But neither the vacuum nor pneumatic-process is so essential in connection with this process as with others where the reducing-liquor is heated while it is in contact with the stock.

Second. The stock, having been prepared by preliminary cuttings, bruising, &c., is packed into the reducing-vessel, as compactly as is desired, by any of the ordinary means of doing the same, after which the reducing-vessel is closed steam-tight, and is connected, by means of strong pipes having stop-cocks in them, with the vessel containing the reducing-liquor, as hereinafter described.

The reducing-liquor is prepared in the usual manner of preparing caustic liquors for treating paper-stock, and of a degree of causticity proportioned to the refractory character of the stock to be treated. For the flag, grape, straw, hemp, flax, and similar fibrous substances, a strength of causticity varying from $\frac{4}{5}^{\circ}$ to 2° Baumé is sufficient. For wood and other more refractory stocks, a strength varying from 3° to 15° Baumé may be necessary. The caustic liquor, when thus prepared, is charged into a vessel capable of being closed steam-tight, and of sustaining an internal pressure of from two hundred to five hundred pounds to the square inch, and it is to be there heated to a temperature considerably higher than the highest temperature desired to be used in the reducing-vessel. As soon as the desired temperature is obtained in the heating-vessel, the stock having been properly packed into the reducing-vessel, and the same having been closed steam-tight, the reducing-liquor is then introduced into the reducing-vessel, and upon and into the stock, by means of turning the stop-cock in the pipe connecting the two vessels. The effect of bringing the liquor and the stock together in the reducing-vessel, in this highly-heated state of the liquor, is to produce an instantaneous action upon all parts of the stock, and the greatest intensity of action on its first introduction to the stock, so that the mode of applying the liquor to the stock is by this process the reverse of all other processes, thus obviating difficulties to which all others are subject. Thus, by the ordinary process of heating the liquors after they have been brought into contact with the stock, causing a progressive action of the liquor upon the stock by the gradual

increase of heat and pressure, until the highest heat and pressure, and consequently the greatest intensity of action, is attained, certain unfavorable results inevitably follow. That portion of the stock first acted upon and reduced to a pulpy condition, while the heat and pressure are increasing, to reach the more interior and refractory portions of the stock, continues subject to the intense action of the reducing-liquor until the whole body of the stock is reduced. Consequently, that portion of the stock is over-treated, and in a great measure destroyed, causing an increased expenditure of alkali, of time, a waste of the stock, and an injurious effect upon the character of the fibre. To obviate these difficulties, many expedients have been resorted to with some effect. The introduction of oleaginous substances to protect the external portions of the stock from the action of the caustic liquor, until the necessary amount of heat and pressure should be produced to reach into all the cells and pores of the stock, produced a favorable result. So, likewise, the resort to the vacuum and pneumatic-processes for the purpose of introducing the caustic liquor to all parts of the stock before the boiling-process should begin, was found beneficial, as tending to produce the result obtained by my improved process. But all these were more or less expensive, and imperfect in their operations and effects. By my process, I at once obtain the benefit of all necessary heat and pressure to carry the caustic liquor into every pore and cell of the stock when they are first brought together in the reducing-vessel, so that the greatest intensity of action takes place at the time when the greatest intensity of action is required, and it acts simultaneously and uniformly upon every part of the stock, and consequently produces a speedy and uniform result, effecting a very great saving of time, chemicals, stock, and producing a very superior quality of pulp.

After the stock and liquor are thus brought together, no more heating of the liquor and stock will be required. After standing and soaking from thirty minutes to two hours, according to the character of the stock, the liquor and stock should be blown off into a washing-tub, with which each reducing-vessel is connected by a large, strong pipe, coming out near the bottom of each reducing-vessel, and closed by means of a large faucet, or other suitable means.

To illustrate the means by which my process is applied, or may be applied, I herewith subjoin the following figures or drawings, which are made a part of my specification:

Figure 1 is a representation of the several vessels used in my process, in a convenient and proper relation to each other, with their respective connections indicated. Thus G G represent two reducing-vessels, to be used alternately; A A represent the man-holes, or places for charging them with the stock to be treated; B represents the vessel in which the reducing-liquor is to be heated preparatory to its introduction to the stock; S S, the pipes connecting such vessel with the reducing-vessels G G; C C represent two pans in which the reducing-liquors are mixed, and the strength thereof adjusted to the character of the stock to be treated; and g g represent the tubes connecting the pans with the heating-vessel B; D represents the washing-tub, into which the stock is to be discharged through the pipes or tubes R R; a a a a, &c., represent a chamber surrounding the heating-vessel B, and partially surrounding the reducing-vessels G G, and constitute a part of the fire-chamber of the furnace E, connecting the furnace with the escape-flues therefrom, and are designed as a means of aiding to heat the liquor in the vessel B, and to keep hot the liquor after it is discharged into the vessels G G. But in practice, so much of the flues a a a as partially surround the reducing-vessels G G, must be closed, so as to exclude the fire therefrom until after the vessels are filled or charged with the reducing-liquor, to avoid burning the stock therein. In any suitable place above these reducing-vessels may be situated the bin H, for containing the prepared stock to be charged into the reducing-vessels G G.

Figure 2 represents a front view of the heating-vessel B, over the furnace E, surrounded by the fire-chamber a a a a, &c., with a partial view of the reducing-vessels G G, and the pipes S S, connecting the heating-vessel B with the reducing-vessels G G and their stops at t t.

Figure 3 represents the reducing-vessels G G, with their connection with the washing-tub D by means of pipes R R and stops y y. It also shows the man-holes A A.

Having thus described my said improvement, I will proceed to set forth my claim.

1. I claim the use of a strong, close vessel for heating the entire liquor to be used in the reducing-vessel to its maximum heat before introducing the same into the reducing-vessel, in combination with the reducing-vessel, substantially in the manner and for the purpose above described.

2. I claim the use of a close vessel, B, in combination with a reducing-vessel, G, to be used with their several connecting-pipes, substantially in the manner and for the purpose above described.

JOEL TIFFANY.
